UNITED STATES PATENT OFFICE

JOSEPH A. PETERSON AND CARL E. OLSEN, OF HOUSTON, TEXAS

TONGS

Application filed December 10, 1929. Serial No. 412,993.

This invention relates to tongs and the like.

It has for its general object the provision of a new and improved tong of great strength but light weight, adapted to be handled with ease and safety.

A more specific object is to provide in a tong of this general type embodying a pair of relatively movable jaws, new and improved means to positively move its jaws together and prevent opening thereof, whereby the pipe or other object to which the tong is applied may be positively gripped before a turning force is applied to the handle to avoid inadvertent disconnection of the pipe and tong and consequent injury to workmen.

Another object is the provision of a tong embodying a plurality of teeth, the construction and disposition of which is such that the pipe or the like to which the tong is applied is not crushed or unduly distorted when a turning force is applied to the handle of the tong; nor are the elements of the tong unduly strained.

Other objects will hereinafter appear.

In the accompanying drawings, which are illustrative of the preferred embodiment of the invention, Fig. 1 is a fragmentary side elevation of the tong with one arm of the fork of its handle removed, the tong being shown as it is initially moved on a pipe; Fig. 2, a view similar to Fig. 1 (with the spring removed), the tong being shown on the pipe; Fig. 3, a fragmentary bottom plan view of the tong; Fig. 4, a horizontal section on the line 4—4 of Fig. 2; and Fig. 5, a view similar to Fig. 2 except that the arm of the fork has been partially replaced and the actuating and locking member has been moved into active position.

The tong embodies a handle 3, forked or bifurcated to provide a pair of arms 3a and 3b; and a pair of jaws 1 and 2, the former pivotally mounted in the fork by means of the pin 4; the latter pivotally and slidably, by means of the pin 5, passing through its slot 2a. The rear ends of the jaws are pivoted together as indicated at 6.

The forward end of the jaw 1 is curved inwardly and provided with a transversely elongated tooth 7.

The jaw 2 has a substantially semi-circular recess 2e at its forward end; transversely elongated teeth 8 and 9 being mounted at its outer and inner forward ends, respectively.

The spring means to effect closure of the jaws includes a spring 15 normally extending from the chamber 2b into the slot 2a. Reciprocable in the slot 2a is a spring guide 10 having an apertured head 11 through which the pin 5 extends.

The spring 15 serves to urge the jaws together to normally effect and yieldably maintain closure of the same by moving and holding the guide 10 forwardly in the slot 2a. See Fig. 2. When the tong is applied to a pipe or the like, as shown by Fig. 1, the jaws are forced apart, the resistance of the spring 9 being overcome by the pin 5 which forces the guide 10 rearwardly in slot 2a. During opening and closing movements of the jaws the pin 5 rotates slightly in the head 11 of the spring guide, but the guide has only a reciprocatory movement in the slot 2a.

Now the teeth 7, 8, and 9 are elongated transversely with respect to the tong and are spaced at substantially equal distances apart when the jaws are about closed. In other words, the teeth 8 and 9 are spaced on the jaw 2 to engage a pipe of predetermined diameter one hundred twenty degrees (120°) apart; and the pivotal mounting of the jaws and the position of the tooth 7 in the jaw 1 are such that the tooth 7 will engage the pipe one hundred twenty degrees (120°) from tooth 8 and from tooth 9. When the tong is applied to a vertical pipe it will be held thereon in a plane substantially perpendicular thereto by the cooperation of said teeth actuated by the spring means. The biting edges of the teeth are then substantially parallel with the axis of the pipe.

Should it become necessary to engage a horizontal pipe from below, the tong may be inverted and moved upwardly into engagement therewith. It will be obvious that in that event, the engagement of the teeth, actuated by the spring means, will hold the tong on the pipe.

For various well known reasons, it frequently becomes necessary to apply great

force to tongs in order to effect the desired rotation of pipes and the like. To prevent slipping of a tong on a pipe, the gripping action must increase with the turning action.

5 Improper gripping, however, crushes or causes undue distortion of the pipe. To prevent this, we construct and arrange the teeth of the tong as shown.

So by the means described, the tong will 10 automatically hold itself in a proper position on the pipe to which it is applied, no matter what the position of the pipe nor how the tong is applied; and the teeth of the tong will be positioned for the desired biting 15 action.

It will be apparent that when the tong is rotated on the pipe in a clockwise direction with respect to Fig. 2, the teeth 7, 8, and 9 will be moved into biting engagement there- 20 with, because the pin 5 will be forced forwardly in the slot 2a to move the jaws together.

Workmen have frequently been injured by inadvertent disconnection of a tong and the 25 object to which it is applied. This occurs frequently in deep well drilling operations in which the workman standing upon a slippery derrick floor throws his weight upon a tong applied to a drill stem to disconnect 30 the sections of pipe of which it is composed. To avoid accidents of this kind, and for other purposes which will be apparent to those skilled in the art, we provide the locking member, preferably in the form of a lever 12 35 pivoted to the handle as indicated at 13 and provided on its forward end with a cam 12a. When the tong is applied to a pipe as shown by Fig. 2, and the locking member 12 is rotated from the position shown by Fig. 2 to the 40 position shown by Fig. 5, the cam 12a will engage the rounded rear end of the jaw 1 adjacent the pivotal connection of the jaws to positively move the jaws together and prevent opening thereof. When the jaws are 45 so moved together, the teeth 7, 8, and 9 will be made to bite the pipe; and so the pipe may be gripped prior to the application of a turning force to the handle. It will be observed, however, that the locking means does not interfere with further gripping movement of the 50 jaws, which will occur should a very great turning force be applied to the handle.

The tong cannot, of course, be removed 55 from the pipe until the locking member has been moved from the position shown by Fig. 5 to the position shown by Fig. 2, and accidental disconnection is, therefore, impossible.

The tong may, of course, be used with the 60 locking member in an inactive position. In that event the handle may be swung back and forth; that is, be given a ratchet movement, to effect a turning of the pipe.

The invention is not limited to the preferred 65 embodiment shown and described. Various

changes may be made, all within the scope of the following claims.

We claim:

1. A tong having a handle, a jaw pivotally mounted on said handle, a jaw pivotally and slidably mounted on said handle, and a locking member to positively move said jaws together and prevent opening of said jaws. 70

2. A tong having a handle, a jaw pivotally mounted on said handle, a jaw pivotally and slidably mounted on said handle, yieldable means to urge said jaws together, and a locking member to positively move said jaws together and prevent opening of said jaws. 75

3. A tong having a handle, a jaw pivotally mounted on said handle, a jaw pivotally and slidably mounted on said handle, said jaws being pivotally connected together, yieldable means to urge said jaws together, and a locking member mounted on said handle and movable into engagement with one of said jaws to positively move said jaws together and prevent opening of said jaws. 80

4. A tong having a handle, a jaw pivotally mounted on said handle, a jaw pivotally and slidably mounted on said handle, said jaws being pivotally connected together at a point to the rear of their connections to said handle, and a locking member mounted on said handle and movable into engagement with one of said jaws at a point to the rear of the pivotal connections of said jaws to said handle to positively move said jaws together and prevent opening of said jaws. 95

5. A tong having a handle, a jaw pivotally mounted on said handle, a jaw pivotally and slidably mounted on said handle, said jaws being pivotally connected together at a point to the rear of their connections to said handle, yieldable means to urge said jaws together, and a locking member mounted on said handle and movable into engagement with one of said jaws at a point to the rear of the pivotal connections of said jaws to said handle to positively prevent opening of said jaws. 100

6. A tong having a handle, a jaw pivotally mounted on said handle, a jaw pivotally and slidably mounted on said handle, said jaws being pivotally connected together at a point to the rear of their connections to said handle, and a lever pivotally mounted on said handle and movable into engagement with one of said jaws at a point to the rear of the pivotal connections of said jaws to said handle to positively prevent opening of said jaws. 115

7. A tong having a handle, a jaw pivotally mounted on said handle, a jaw pivotally and slidably mounted on said handle, said jaws being pivotally connected together at a point to the rear of their connections to said handle, and a lever pivotally mounted on said handle and having a cam movable into engagement with one of said jaws at a point to the rear of the pivotal connections of said 120

125

130

jaws to said handle to positively prevent opening of said jaws.

8. A tong having a handle, a jaw pivotally mounted on said handle, a jaw pivotally and slidably mounted on said handle, said jaws being pivotally connected together, a tooth mounted on one of said jaws, a pair of teeth mounted on the other of said jaws, said teeth being at substantially equal distances apart

10 when said jaws are in predetermined positions with respect to each other.

9. A tong having a handle, a jaw pivotally mounted on said handle, a jaw pivotally and slidably mounted on said handle, said jaws being pivotally connected together, a tooth mounted on one of said jaws, a pair of teeth mounted on the other of said jaws, said teeth being transversely elongated and at substantially equal distances apart when said jaws

20 are in predetermined positions with respect to each other.

10. A tong having a handle, a pair of relatively movable jaws mounted on said handle, a tooth mounted on one of said jaws, a pair of teeth mounted on the other of said jaws, said teeth being at substantially equal distances apart when said jaws are in predetermined positions with respect to each other, and a locking member to positively

25 move said jaws together and prevent opening of said jaws.

11. A tong having a handle, a jaw pivotally mounted on said handle, a jaw pivotally and slidably mounted on said handle, said jaws being pivotally connected together, a tooth mounted on one of said jaws, a pair of teeth mounted on the other of said jaws, said teeth being at substantially equal distances apart when said jaws are in predetermined

30 positions with respect to each other, and a locking member mounted on said handle and movable into engagement with one of said jaws to positively prevent opening of said jaws.

45 In testimony whereof, we hereunto affix our signatures.

JOSEPH A. PETERSON.
CARL E. OLSEN.
